UNITED STATES PATENT OFFICE.

PETER A. JOHNSON, OF ST. PAUL, MINNESOTA.

FOLDING SLED.

No. 831,513.

Specification of Letters Patent.

Patented Sept. 18, 1906.

Application filed February 6, 1906. Serial No. 299,817.

To all whom it may concern:

Be it known that I, PETER A. JOHNSON, a citizen of the United States, residing at St. Paul, in the county of Ramsey and State of Minnesota, have invented certain new and useful Improvements in Folding Sleds; and I do declare the following to be a full, clear, and exact description of the invention, such as will enable others skilled in the art to 5 to which it appertains to make and use the same, reference being had to the accompanying drawings, and to the figures of reference marked thereon, which form a part of this specification.

15 This invention relates to improvements in sleighs and sleds; and the main object is to provide a sled that may be folded together or knocked down and held in the folded position during storage and transportation, the 20 latter including not only transportation in shipment of large numbers, but also where, for instance, a single sled is carried by a person along any kind of pathway and then unfolded, loaded, and drawn with the load on it 25 over a proper road to the destination of the load, this applying also where dogs or other draft-animals are used. This and other objects I attain by the novel construction and arrangement of parts illustrated in the accompanying drawings, in which—

Figure 1 is a top view, and Fig. 2 is a side elevation, of my folding or knockdown sled. Fig. 3 is a rear elevation of one corner of the sled. Fig. 4 is a bottom view of the cross-bar 35 9 in Fig. 3. Fig. 5 is an end view of the cross-bar uniting the front ends of the runners. Fig. 6 is a rear elevation of the cross-bar in Fig. 5 with a screw-rod added. Fig. 7 is a top view of the sled in its folded position with 40 substantially all parts shown. Fig. 8 is a side elevation of Fig. 7 with the screw-hooks in heads of runners omitted. Fig. 9 is a bottom view of the main upper parts of the sled folded ready to be inverted and secured upon the runners, as in Fig. 8. Fig. 10 is a detail 45 top view of one of the metallic plates or steps secured upon the runners for the support and fastening of the upper parts of the sled. Fig. 11 is a side or edge view of Fig. 10.

50 Referring to the drawings by reference-numerals, 1 1 are the two runners of the sled. These have in the folded position of the sled their front ends secured together by a short

screw-rod 2, having an eye 3 to turn it by and at its end screw-threads engaging in a nut 4, 55 secured in one of the runner-heads, while a washer 5, secured in the other runner-head, meets the ring 3, the rod passing through the two heads. When the sled is set up or unfolded, this short rod is carried in two eye-bolts 6 6^a upon the cross-bar 8 of the sled, the eyebolt 6^a being screw-threaded to hold the threaded end of rod, while the runner-heads are secured together by a longer screw-rod 10, which being inserted as shown in Figs. 1 60 and 2 holds the mortises 11 of the heads firmly upon the tenons 12 of the head cross-bar 7, the rod passing through the eyebolts or staples 13 of the bar. Said bar has a central hole 14 or other means to which a rope may 65 be fastened for draft-animals hitched for drawing the sled.

Upon each runner are secured two metallic plates 15, formed with shallow pockets 16, which steady both sides and the rear of the 70 lower ends of uprights 17. Said uprights have their upper ends formed with tenons 18, which when the sled is set up are inserted in mortises 19 in the cross frame-bars 8 and 9, and upon the latter are secured by pivots 20 the 75 longitudinal bars 21, which have their pivot-holes 22 slotted to allow the pivots to move toward the middle of the bar when the sled is folded, so that the framework will not be 80 any longer than the runners when folded, as 85 shown in Fig. 7.

The uprights 17 are braced in the upright position by the yoke-shaped rear braces 23, joined at 24, one upon the rear side of each post and having the lower end pivotally engaging 90 at 25 the plate 15. They are further braced by being pivotally connected in pairs or as many uprights as there are on one runner by a horizontal brace 26 and by the brace-yoke 27, extending therefrom, being pivoted at 28 95 and engaging the screw-hook 28^a, sliding in the head of the runner and having a thumb-nut 29 forcing it forward and a tight nut 30 to prevent the thumb-nut from getting lost. Against transverse folding the uprights are 100 braced by being inserted in the bars 8 and 9 and by having each an oblique brace 31, (best shown in Fig. 3,) pivoted at 32 to the cross-bar and having a hole 33, going upon a staple 34, secured in the upright, and a pivoted 105 hook 35, carried by the brace and engaging

the staple, so as to keep the brace on it. When the sled is folded, said braces are placed with their apertures 33 upon revoluble eyebolts 36 (see Fig. 8) and retained there by 5 turning the eyebolt with its eye out of line with or across the aperture in the brace.

While the braces are thus held their hooks 35 are hooked into staples 37 in the runners, and thus hold the folded upper parts of the 10 sled secured upon the runners, as shown in Fig. 8, the parts being first folded, as in Fig. 9, where it will also be seen that a special brace-hook 38 is pivoted at 20^a and engages a pin 40 to help hold the parts together in 15 folded position. When said hook is not in use, it is held secured below the bar 9 by engaging the pin 41 in said bar, as shown in Fig. 4.

In the folded position of the sled the rod 10 and bar 7 occupy the position shown in Fig. 20 9, the rod being screwed into the same staple 9, the rod being screwed into the same staple or eyebolt 6^a that receives the end of the short 25 rod in Fig. 1.

The rear ends of the runners are held together by a double hook 42, pivoted upon 25 30 one runner and engaging with one of its hooks the pin 43 in the other runner, and when the sled is set up the hook is held steady in its idle position by having its other hook firmly engaged with a pin 44, fixed in the runner carrying the hook.

Near the ends of the cross-bars 8 and 9 I provide holes 46, serving as stick-pockets for 35 insertion of suitable sticks (not shown) to help hold a bulky load on the sled.

In the present instance the braces 23 have their lower ends pivoted to the runners by being passed into the groove 25 in the under 40 side of the plate 15, and the pockets 16 are open at their front side, as the uprights are firmly braced against motion forward with the lower ends; but it is obvious that such and many other details may be modified without diverging from the scope and spirit of 45 my invention.

In using the sled the load is placed upon the bars 21, either directly or indirectly, by placing first upon the bars supporting means suitable for the articles to be hauled.

Having thus described my invention, what 50 I claim as new, and desire to secure by Letters Patent, is—

1. A sled comprising a pair of detachably-connected runners, a detachable bar between 55 the heads of the runners, a long screw-rod passed through the heads and adapted to draw the heads together against the ends of the bar, and a shorter screw-rod to take the place of the long one and hold the heads close 60 together when the bar is removed, and a hook securing the rear ends of the runners together when the sled is folded, and means for holding the idle rod when the other rod is in use, substantially as set forth.

2. A sled having its runners detachably secured together, foldably-secured uprights upon the runners, braces for holding the uprights set up, a foldable frame or platform mortised upon the ends of the uprights and braces carried by the frame and adapted to 70 be detachably secured in an oblique position to the uprights.

3. A sled comprising a pair of detachably-connected runners, foldable uprights secured upon the runners by links or braces connecting their rear sides with the runner, a folding frame detachably mounted upon and braced to said uprights, a brace connecting together all uprights on each runner, a brace pivoted to the front upright, and a screw-hook engaging said brace, said hook being slidably inserted in the head of the runner and provided with an adjustment-nut for stretching and releasing the brace.

4. A sled comprising a pair of detachably-connected runners, foldable uprights secured upon the runners by links or braces connecting their rear sides with the runner, a folding frame detachably mounted upon and braced to said uprights, a brace connecting together 90 all uprights on each runner, a brace pivoted to the front upright, and a screw-hook engaging said brace, said hook being slidably inserted in the head of the runner and provided with an adjustment-nut for stretching and 95 releasing the brace, the oblique braces 31 arranged to resist side pressure on the uprights, the hooks 35 pivoted to the braces and adapted to engage staples 34 in the uprights when the sled is set up and the staples 37 in the 100 runners when the sled is folded; and revoluble eyebolts 36 for holding the braces in hori-zontal position when the sled is folded.

5. A folding sled having a detachable load-supporting frame made up of transverse bars 105 and longitudinal bars pivoted thereon with slideable pivot-joints, the hook 38 for holding said frame in the folded position, and means for holding said hook out of the way when not in use, substantially as and for the purpose specified.

6. In a folding sled, the combination with two detachable runners, of a frame-bar adapted to be inserted between and partly into the heads of the runners, staples or guides upon 115 said bar, a screw-rod passing through the runner-heads and drawing the heads tightly against the ends of the bar, said rod being guided by the staples on the bar.

7. In a folding sled, the combination with 120 the runners 1, of the plates 15 secured thereon and having the pocket 16 and groove 25, a post or upright placed in each pocket and a yoke-shaped brace adapted to straddle the upright when folded, said brace being connected with the grooved part of the plate, the brace-bar 26 connecting the uprights on the same runner, the brace 27 pivotally connected 125

with the front end of the brace 26, the adjustable screw-hook in the runner-head adapted to engage the front end of the brace 27, all substantially as and for the purposes set forth.

5 8. A sled having a detachable platform made up of transverse and longitudinal bars or slats pivoted together at their crossings, so that they may by turning on the pivots be

brought together and reduce the size of the platform.

In testimony whereof I affix my signature in presence of two witnesses.
